ATTORNEYS.

UNITED STATES PATENT OFFICE.

DANIEL O'REARDON, OF JERSEY CITY, NEW JERSEY.

DESIGN FOR A BOTTLE.

SPECIFICATION forming part of Design No. 22,380, dated May 2, 1893.

Application filed February 21, 1893. Serial No. 463,258. Term of patent 14 years.

To all whom it may concern:

Be it known that I, DANIEL O'REARDON, of Jersey City, in the county of Hudson and State of New Jersey, have invented and produced 5 a new and original Design for a Bottle, of which the following is a full, clear, and exact specification.

Reference is to be had to the accompanying drawings forming a part of this specification, in which—

Figure 1 is a perspective view of a bottle embodying my new design; and Fig. 2 a transverse section thereof.

The design consists in the configuration

shown. Thus the body is of antique appearance, its front and rear sides as seen in profile having a general forward inclination, though not pronounced, and from its upper side near one end the lines of the neck depart with a slight forward inclination. At the sides of 20 the body appear irregularities of surface.

I claim—

The design for a bottle herein shown and described.

DANIEL O'REARDON.
